UNITED STATES PATENT OFFICE.

ISAAC A. BAUM, OF CHICAGO, ILLINOIS.

METAL FRAME FOR DOORS.

Application filed March 6, 1928. Serial No. 259,431.

My invention relates to means for framing door openings and particularly to means for joining the ends of all metal frames.

I am aware that metal frames of different forms have been devised but many thereof are so constructed that they must be assembled and permanently united in the shop, necessitating shipping and handling in assembled condition. This is undesirable for many reasons.

One object of my invention is to provide a frame composed of elements of the proper shape and having associated therewith suitable means enabling the respective frame elements to be assembled and rigidly joined in the field. In the construction shown, this is accomplished by very simple elements and the assembly is simply effected by the seating of a few screws. The resulting structure is firm and rigid and insures a perfect miter joint.

Another improvement disclosed in connection with the parts illustrated is in the means for readily placing and anchoring the frame preliminary to the laying of the wall. This means comprises a wood block simply secured in the frame and adapted to form a means of connection with vertical struts or braces extending downward from the ceiling.

The invention will be more readily understood by referring to the accompanying drawings, in which—

Fig. 1 is a side elevation of a corner of a frame arranged in accordance with my invention;

Fig. 2 is an elevation from one edge of the frame shown in Fig. 1;

Fig. 3 is a plan view thereof;

Fig. 4 is a sectional view on the line 4—4 of Fig. 1;

Fig. 5 is a perspective view showing the relation of two separated attaching channels;

Fig. 6 is a sectional view on the line 6—6 of Fig. 7 showing a slightly modified construction;

Fig. 7 is a plan view of the construction shown in Fig. 6, and

Figs. 8 and 9 are perspective views of two attaching elements.

In the construction shown in Figs. 1 to 5 inclusive, I have illustrated portions of a frame or casing consisting of vertical and horizontal elements of duplicate form or cross sectional shape. The cross section of the casing is best shown in Fig. 4 in which it will be seen it comprises a jamb 10, a stop 11

formed outwardly from the metal of the jamb, a flange 12 constituting a decorative trim and a rebent margin 13 acting as a plaster terminal. This may be duplicated on the two 60 sides of the frame.

As best shown in Fig. 1, the ends of the vertical and horizontal members are mitered and an object of the invention is to provide sure and certain means for effecting a close fit of 65 the miter joint. To this end, I provide a pair of attaching elements in the form of short channels best shown in Fig. 5. The channels comprise a web 14, side flanges 15, ears or lugs 16 bent inwardly from the ends of the 70 flanges 15 and a tongue 17 projecting from the web 14. The lugs and tongue are suitably apertured. It will be noted that the channels are, in effect, exact duplicates, the upper 75 being fitted snugly within the channel of the cross frame member and the lower being similarly fitted within the vertical frame member. When fitted in place and permanently welded the vertical and horizontal members of the frame, with the apertures in 80 the lugs in registering relation, may be accurately drawn together by the use of screws thus insuring an accurate fitting of the miter joint.

As an additional means for insuring a more 85 rigid connection and to prevent distortion during the process of setting of the frame I provide the L shaped side plates, two of which are employed, one at each side of the attaching channels. One leg 18 of the L 90 shaped plate is welded to the flanges 15 of the attaching channel in the cross member of the frame while the other leg 19 lies along side of the corresponding flanges of the lower attaching channel. Registering holes provided 95 in the plate and the flanges of the channel accommodate bolts or screws 20 as best shown in Figs. 1 and 4. At the inner marginal edge of the L shaped plates I provide the angular flange 21 which abuts snugly against a portion 100 of the trim 12 of the frame.

The side plates being welded to the cross member of the frame and being firmly held by bolts to the vertical member of the frame insures a rigid connection and avoids any strain 105 or distortion on the fastening screws at the miter.

As a means for stiffening the two plates and to serve as a mounting for a wood block 22, I provide a short channel section having a 110 web 23 and side flanges 24 that fits between the two legs 19 of the plates and may be weld-

ed thereto. The wood block is held by means of nails 25 extended through the plate and flanges 24 as shown. This wood block serves as a means of ready attachment of braces or struts for temporarily holding the door frame in position while the wall is being laid. After the wall has been laid to a certain height the braces including the block 22 are knocked out and the space between the flanges receive 10 the tile or other form of wall.

In the construction in Figs. 6 to 9 inclusive the frame or casing elements are identical with those already described. However, the attaching elements differ somewhat in that 15 they are arranged in right lines instead of diagonally as shown in the construction just described. The attaching channels are best shown in Figs. 8 and 9. The upper channel shown in Fig. 8 comprises a web 26 which may be welded to the jamb, side flanges 27 and apertured ears or lugs 28 integral with the side flanges. The lower channel comprises a web 29 having apertures therein and which is welded to the jamb of the vertical frame element, and side flanges 30 having apertures 25 31 therein. When the parts are positioned as shown in Fig. 6 screws 32 may be passed through the registering apertures to securely 30 draw the frame element into the proper meeting relation of the miter joint.

As in the construction of Figs. 1 to 5, I provide side plates 32 of angular outline which are welded to the flanges 27 of the upper element and which are apertured to accommodate bolts 33 passing through the plates and aperture 31 in the lower attaching element. Similarly I provide a cross channel 34 extending between the plates and acting as a seat for a wood block 35.

In each of the constructions the assembly is very simply accomplished with the assurance that an exact fit of the parts will result. A firm and rigid frame is insured at comparatively small expense. Furthermore the simple 45 means for attachment of bracing or position-

ing means will commend itself to those required to install the frames.

Modifications other than those disclosed herein will undoubtedly suggest themselves to others and I do not wish to be limited except as indicated in the appended claims. 50

I claim:

1. In a metal door frame a combination with vertical and transverse elements, metal members secured to one of said elements and projecting in to the plane of another element and adapted to be secured thereto to retain the elements in proper relation and a wood block secured to one of said metal members and adapted to act as a temporary means for use 55 in positioning and holding the frames between a floor and ceiling.

2. In combination, vertical and horizontal frame members including integral jamb and trim, channel members welded to said vertical and horizontal members and having registering apertured portions adapted to receive holding means, and means for securing a temporary wood block to one of said channel members for use in positioning said frame 60 between a floor and ceiling. 70

3. In combination, vertical and horizontal door frame elements each consisting of a sheet of metal bent to provide integral jamb, stop and trim elements, a metal holding device welded to respective vertical and horizontal frame members and provided with cooperating apertured wing portions adapted to receive screws for accurately positioning the frame elements at their corners, and additional metal members welded to one of said frame members and projecting around the corner into adjacent cooperative relation to the other frame element, and additional holding means 75 associated with said additional member and said cooperating frame member. 80

In testimony whereof I have affixed my signature.

ISAAC A. BAUM.
